RAZOR

Marko M. Marusich, Clairton, Pa., assignor of
one-half to Jack Vulich, Chicago, Ill.

Application January 12, 1933, Serial No. 651,380

5 Claims. (Cl. 30—12)

This invention relates to a razor and more particularly to a straight razor having a removable blade section which when in assembled position in the holder will have generally the same appearance as a straight razor.

One of the objects of the invention is the production of a straight razor other than a so-called safety razor, which can be vigorously manipulated for stropping and which may be employed in general use as a straight razor, yet possessing the advantages of having a detachable blade section which may be detachably removed from a permanent back and be replaced by another blade section.

15 A further object of the invention is the production of a razor having a detachable blade portion which may be removed and replaced in a permanent holder by a simple swinging movement of the blade with respect to the holder or permanent back, thus avoiding any necessity of longitudinal sliding movement of the blade in the taking apart and assembling operation.

A further object of the invention is the provision of a razor comprising a holder and blade section presenting a continuity of side surfaces and an improved blade fastening means cooperating with the holder and engaging on both sides of a portion of the blade to firmly position the same within the holder against possibility of accidental displacement when vigorously manipulated by a user in stropping or other operations.

This application is a continuation in part of subject matter included in the copending application Serial No. 507,692, filed January 9, 1931.

35 The razor structure embodies generally a longitudinally slotted blade holder or permanent back having a removable blade section with a reduced shank portion seated, when assembled with the holder, against longitudinal movement, with the reduced shank portion within the slotted back securely fastened therein by a leaf spring controlled means which in normal fastening position has its outer surfaces substantially in continuation of the surfaces of the permanent back or holder. The structure is reflected in detail in the description hereinafter set forth and in the drawing forming a part of this specification.

40 In the drawing:—
50 Fig. 1 is a side elevation of a razor in accordance with the invention, the position of the inserted blade being shown in dotted lines.

Fig. 2 is an enlarged perspective view broken away of the holder showing the organization therewith of the locking means.

Fig. 3 is a longitudinal sectional view of the holder and blade positioned in the holder.

Fig. 4 is a cross sectional view of the holder and blade taken on line 4—4 of Fig. 1.

Fig. 5 is an elevational view of the blade member.

Fig. 6 is a cross sectional view taken on the line 6—6 of Fig. 1.

While straight razors having a detachable blade section have been previously made, such

10 structures have been proven unsatisfactory and unsuitable for practical use, because of the fact

that blade sections have either been hooked over the permanent back or fastened therein or there-

15 to by fastening means capable of being accidentally dislodged, or which destroy the razor balance and interfere with operation of the razor as an ordinary razor could be used. It is im-

perative, due to the frequent vigorous manipula-

20 tion of a straight razor in stropping, honing, 15

grinding, and use, that there be no portions ex-

tending beyond the side surfaces of the blade 20

holder, otherwise the blade may be accidentally 25

loosened from its holder resulting in damage 25

or injury. Straight razors are almost universal-

25

ly used by barbers and become subjected to vigor-

ous manipulation in use and in grinding fre-

quently the temper of the blade is destroyed, 30

necessitating the discard of the entire razor

35 structure. The applicant's invention obviates

the necessity of discarding other than the blade

35

portion when temper is destroyed or the cut-

40

edge becomes otherwise unuseful by break-

age or the like and presents a razor structure

45

which has the same balance and identical ap-

pearance found in a conventional straight razor.

Referring particularly to the drawing, the razor

40 of the invention includes a permanent metal back

or blade holder member 1, pivoted in a conven-

50 tional razor handle 2, so that the back may be

folded within the sides of the handle in the man-

ner of an ordinary razor. The back or holder

55 may be made from any suitable hard metal and

is rounded at the top and provided with a flat sur-

face on the under side extending throughout a

portion of its length, providing a seating surface

55 for a detachable blade portion hereinafter de-

scribed. The back or holder portion has a cen-

tral longitudinal slot 3 entering the under side of

55 the holder extending from a point adjacent the

pivoted end of the holder through its free end.

The slot which is designed to receive and seat a

portion of a blade structure is closed at the

55 free end of the holder by an angular metal insert

4 lying flush with the end and lower face of the

55

holder. The insert is fixed in the slot by a pin or rivet 4' passing through the depending side portions of the holder and the insert. The insert has one of its sides upwardly inclined, within the holder, toward the free end to provide an overhang for the slot and a seat for an angular projection on a blade to be accommodated within the holder. The slot is of uniform depth in the holder except at the rear or end opposite the insert where the bottom wall is curved toward the surface of the holder to define a seat for a blade portion which when inserted may be swung into position to be locked within the holder.

While different metals may be employed for the blade holder just described, the blade portion 5 of the razor is made from razor steel, but due to its novel structural characteristics is hardened only throughout a portion of its width, the portion of the blade engaging the holder being unhardened. The blade portion 5 has its sides hollow ground, as at 6, to present an extremely thin cross sectional area throughout the cutting portion of the blade. This blade is provided with a central longitudinally extending reduced shank 7 which is so proportioned as to be received within the slot formed in the holder to provide a snug fit. The central shank portion of the blade 7 defines longitudinally extending shoulders 8 on opposite sides of the blade which closely engage the longitudinal bearing surfaces on each side of the slot on the under side of the permanent back or holder. This engagement, when the blade is inserted within the holder, is such that the joint formed between the holder and blade presents substantially a continuity of surfaces with respect to the sides of the blade and the holder portion which on its opposite sides is concaved to conform to the general shape of an ordinary razor blade.

The blade portion is provided in the reduced shank portion adjacent the forward end with an undercut forming the angular extension 9 which fits behind the insert 4 overhanging the forward end of the slot permitting the blade to be swung into a position with the shank snugly engaging in the slot formed in the holder. The opposite or rear end of the shank is extended at 10 beyond the main cutting portion of the blade and is rounded to cooperate with the slotted holder and the locking means hereinafter described. The extension 10 beyond the end of the main portion of the blade is somewhat wider than the longitudinally extending portion of the shank above the main blade portion and the longitudinally extending shoulders join side shoulders 11 arranged to cooperate with similar shoulder portions 12 of the holder so that when in the assembled position in the holder, the blade will be fixed between two longitudinally disposed points against longitudinal movement with respect to the permanent back or holder.

The permanent back is provided with concave side surfaces throughout substantially the extent of the main blade portion and adjacent the rear end of said blade portion is slightly widened, defining the shoulders 12 for seating the shoulder portions of the blade. The permanent back is cut away adjacent the blade holder portion defining a recess 13 having a curved rear end wall 14. The recess 13 extends forwardly to a point beyond the rear end of the longitudinally extending slot in the holder so that a small portion of the extension 10 of the blade shank will project slightly above the bottom of the forward end of the recess. A flat latch member or spring 16 conforms in shape

to the recess 13 and is pivotally fixed substantially at its center in the cut away portion by a suitable pin or rivet 17 passing transversely through the holder. The forward end of the latch member is biased toward the permanent back and may be swung laterally to and from its registering position in the cut away portion of the back into and out of contact with the shank extension and end of the blade. To facilitate this operation, the side of the holder is recessed at 18 to permit insertion of the finger nail of a user to slightly lift the end of the latch member, and the forward end of the latch has a depending side flange 19 normally seated flush with the holder in a side recess 20 in the holder. The end of the latch spring is provided centrally on the lower side with a slot or depression 21 defining side shoulders 21 and is designed to engage the curved extending edge of the blade shank extension 10 exposed in the forward end of the recess formed by the cut away portion to firmly lock the blade in position in the holder.

Where a blade is within the holder, the latch spring lies within the recess 13 to form a continuity of the surfaces of the permanent back or holder minimizing the chance of accidental dislodgment of the latch to release a blade but such accidental release is further positively prevented by the central pivoting of the latch spring which occupies a position in which the fingers normally grasp the razor for stropping and honing purposes. In the arrangement shown, the finger pressure will fall on both sides of the pivot pin tending to hold the latch in position. The depending flange 19 affords a further safe guard.

From the structure described, it will be observed that the flattened lower surfaces and the vertical shoulders of the holder cooperate with the longitudinally extending and vertical shoulders of the blade to form a firm seating engagement, which, coupled with the snug fit of the shank portion and its engagement forward, results in a very rigid structure firmly held in position by the locking means.

To insert a blade section in the permanent back, it is only necessary to engage the angular projection of the blade shank with the portion overlying the forward end of the slot, whereupon the blade may be swung upwardly into the holder with the end of the shank extension exposed in the locking recess. The leaf spring locking means is pushed laterally by means of the depending flange into registry with the cut away portion of the holder to engage the edge of the shank extension in the depression in the spring. In moving the spring into engagement with the blade extension the spring flexes in passing the blade and automatically seats thereon when the slot or depression is above the edge of the shank extension. To remove the blade section the spring is slightly lifted and swung to the side in which position the blade section may be removed by a slight pull at the rearward end. No longitudinal movement of the blade section likely to cut the hand of a user is necessary for the pull in dislodging a blade is always away from the cutting edge. It will also be noted that when the blade is seated there are no projection parts of anchoring means for the blade or of the detachable locking means. The importance of this feature is obvious when considering the ordinary use of the article.

The construction hereinbefore described affords all of the advantages of a straight razor and obviates the disadvantages of locking means

which might be accidentally released and the entire structure lends itself to economical manufacture and the possibility of using different metals for the permanent back or holder member 5 and the blades. Hitherto it has been necessary to use in straight razors, razor steel throughout, and such steel is expensive and when accidentally dropped any damage to the fragile edge of the razor has necessitated replacing the entire blade.

10 In this construction, a permanent back is supplied which may accommodate either a round-nose blade or a sharp-cornered blade, as the user desires. The advantages of the construction reside in the permanency of the fastening means, 15 maintaining the identical balance of a conventional straight razor, and the manner of mounting the blade shank completely within the holder to provide no extensions which might be caught by the hands of the user or which could receive 20 and hold dirt.

I claim:

1. In a razor, a permanent back or blade holder having a series of stepped longitudinally extending flat bottom surfaces defining vertical shoulders therebetween and a longitudinal slot extending inwardly of the holder and throughout one of the stepped portions and into an adjacent stepped portion of the holder, an insert flush with the surfaces of the holder overlying and closing the slot at one end of the holder and forming a seat for an extension on a blade member, a detachable blade having a reduced longitudinally extending shank for engagement within the longitudinal slot of the holder, one end of the shank 35 being undercut to seat behind the insert and the other end of the shank being extended beyond the blade portion, said reduced shank portion defining oppositely disposed longitudinally extending horizontal shoulders for seating engagement 40 with the bottom of the holder and vertically disposed shoulders for cooperation with the vertical shoulders on the holder defined by the stepped portion, and a spring latch coinciding with one of the stepped portions and pivotally mounted at 45 substantially its center whereby it may be swung into and out of engagement with the shank extension and the end of the blade portion engaging the vertical shoulders.

2. As a new article of manufacture, a razor 50 blade hardened throughout its length but through only a portion of its width, and having a reduced longitudinally extending shank portion longer than the main blade portion defining longitudinally extending shoulders terminating in vertical 55 shoulders on opposite sides of the blade, said shank portion having one end undercut to define an angular extension and the other end extended

beyond the main blade portion and slightly below the longitudinally extending shoulders.

3. In a razor, a blade holder having a longitudinal recess intermediate its ends defining an angularly disposed shoulder at one end, shoulders formed on the holder adjacent the opposite end of the recess on opposite sides of the recess and extending upwardly from the bottom of the recess to form stepped portions on the holder, a blade for cooperation with the holder having a longitudinally extending shank terminating in an angularly disposed shoulder for cooperation with the shoulder defined by the recess, said blade also having shoulders formed at the opposite end of the blade for cooperation with the shoulders on the holder formed between the stepped portions of the holder, and means for forcing the end of the shank and the shoulders on the blade into engagement with the shoulders on the holder respectively whereby the blade is compressed in position between the end of the recess and the shoulders formed by the stepped portions of the holder. 10 15 20

4. In a razor, a blade holder having a longitudinal recess intermediate its ends defining an angularly disposed shoulder at one end, shoulders formed on the holder adjacent the opposite end of the recess on opposite sides of the recess and extending upwardly from the bottom of the recess to form stepped portions on the holder, a blade 25 for cooperation with the holder having a longitudinally extending shank terminating in an angularly disposed shoulder for cooperation with the shoulder defined by the recess, said blade also having shoulders formed at the opposite end 30 of the blade for cooperation with the shoulders on the holder formed between the stepped portions of the holder, and a spring latch member pivoted substantially at its center on the holder for engaging and forcing the end of the shank and the shoulders on the blade into engagement with the shoulders on the holder respectively whereby the blade is compressed in position between the end 35 of the recess and the shoulders formed by the stepped portions of the holder. 40 45

5. As a new article of manufacture, a cutting blade for a razor having a reduced shank portion defining longitudinally extending shoulders joining vertical shoulder portions on opposite sides of the blade, said shank portion having one end 50 short of the end of the blade and undercut to define an angular extension and the other end rounded and extending beyond the main blade portion and having a flat shoulder slightly below the longitudinally extending shoulders. 55

MARKO M. MARUSICH.
